HERMAN R. FREUND, OF BROOKLYN, NEW YORK, ASSIGNOR TO INTERTYPE CORPORATION, OF BROOKLYN, NEW YORK, A CORPORATION OF NEW YORK.

MATRIX FOR TYPOGRAPHICAL MACHINES.

Application filed May 10, 1923. Serial No. 638,051.

The present invention relates to improvements in matrices of the kinds adapted for use in typographical machines and it is applicable more particularly to matrices of the kind used in machines of the linotype class, substantially as shown and described in Letters Patent No. 436,532, granted to O. Mergenthaler.

The primary object of the invention is to provide matrices of novel and improved construction, whereby matrices belonging to one font or set may be distinguished and distributed separately from those belonging to other fonts or sets, thus insuring, for example, the return of all matrices used in the machine to the proper magazines in which they are stored. When so used, the improved matrices are particularly adapted for machines capable of assembling mixed lines, i. e., lines made up of matrices belonging to two or more fonts to enable a type slug to be cast against the character bearing edges of the matrices. Other uses for the improved matrices may suggest themselves, where it is desirable or necessary to separate and distribute according to font. The improved matrices, although embodying font distinguishing means, possess further practical advantages in that they may have the usual outline of the ordinary matrices commonly used in machines of the linotype class and they may at all times be used in such machines in the manner usual with the ordinary matrices.

In the accompanying drawing:—

Figure 1 is a perspective view of a matrix constructed in accordance with the present invention;

Figure 2 represents a transverse section through a plurality of matrix channels and illustrating the relative positions occupied therein by matrices made in accordance with the present invention and belonging to four different fonts;

Figures 3, 4, 5 and 6 are, respectively, collective views showing in side view and end view matrices constructed in accordance with the present invention and belonging to four different fonts; and

Figure 7 represents a vertical section through a matrix channel showing one form of distributor adapted to separate and distribute matrices like those herein shown according to font.

Similar parts are designated by the same reference characters in the several views.

The present invention is applicable generally to matrices of various kinds suitable for use in line casting machines wherein matrices each bearing a character are assembled to form a line from which a cast may be taken to obtain a type bar or slug. The invention, however, is more particularly applicable to matrices of the kind used in machines of the linotype class, as hereinbefore referred to. The preferred embodiment of the invention is shown in the accompanying drawing and will be hereinafter described in detail, but it is to be understood that the invention is not restricted to the precise constructions shown, as equivalent constructions are contemplated and these will be included within the scope of the claims.

As shown in the present instance, each matrix has the same general form and outline as the ordinary matrix commonly used in machines of the linotype class, it comprising a body m having guiding lugs or ears m^2 projecting from its corners and having a matrix character m^x formed in one of its longitudinal edges, it being common to provide some matrices with a single matrix character and other matrices with two matrix characters. One end of the matrix which constitutes the upper end thereof when the matrix is in upright position in the machine, as, for example, during the casting operation, is notched and provided with permuted teeth m' which are adapted to cooperate in the usual way with the similarly permuted distributor bar of the machine, so that the matrices will be suspended on the distributor bar and will travel along it until released at the proper points which are determined according to the characters of the font which the matrices bear so that the matrices may be separated according to character by distributing means similar to that commonly used in machines of the linotype class. The matrices embodying the present invention may be of the same size and general outline as those commonly used in machines of the linotype class, and the lugs or ears m^2 may perform the functions of the lugs or ears of the ordinary matrices of this kind.

According to the present invention, the matrices are provided with means by which

those belonging to different fonts may be distinguished and mechanically separated from one another. In the particular embodiment of the invention shown, the matrices belonging to one font or set are provided with a recess or groove m^3 which extends longitudinally from end-to-end and in one of the flat faces of the matrix, a matrix M^3 formed in this way being shown in Figure 3. All matrices belonging to a given font or set may, therefore, be distinguished by the characteristic recess or groove m^3 in its flat side. All matrices belonging to another font or set may be distinguished by a recess or groove m^4 formed in the flat side of each of these matrices and extending longitudinally thereof from end-to-end, the wall of the recess or groove adjacent to the longitudinal edge of the matrix being notched to form permutations m^7 . The matrix M^4 (Fig. 4) and containing the characteristic recess or groove m^4 and permutations m^7 would be representative of all matrices belonging to a second font. The matrices belonging to a third font may be distinguished from other fonts by forming them in the manner represented by the matrix M^5 (Fig. 5), each of these matrices being formed with a recess or groove m^5 which extends longitudinally in one of the flat faces of the matrix and from end to end thereof, the edge or wall of the recess adjacent to the longitudinal edge of the matrix being suitably notched in a distinctive manner to form permutations m^8 . All matrices belonging to a fourth font or set may be distinguished from other fonts by forming such matrices in the manner represented by the matrix M^6 of Fig. 6, each of these matrices having a recess or groove m^6 formed longitudinally in one of its flat faces and extending from end to end of the matrix, the edge or wall of the recess or groove adjacent to the longitudinal edge of the matrix being notched in a distinctive way to form permutations m^9 which are characteristic of all matrices belonging to this particular font. Obviously, by using additional notches or permutations the font distinguishing means may be extended to a larger number of fonts of matrices.

Matrices belonging to different fonts and provided with font distinguishing means in accordance with the present invention may be used in connection with devices of different kinds for effecting separation and distribution of such matrices according to fonts. For example, such matrices may be used advantageously in connection with typographical machines which embody a plurality of magazines containing respectively matrices of different fonts and from which the matrices may be drawn to assemble mixed lines, and such machines may embody matrix distributing mechanism similar to that shown and described in my companion application

Serial No. 638,052 filed of even date herewith, according to which the matrices are first separated according to character and the matrices thus separated are then separated according to fonts and are distributed to the appropriate magazines. Figures 2 and 7 herein represent portions of the font distributor which is shown and described more fully in my companion application, these figures, however, being believed sufficient to disclose the manner in which matrices belonging to different fonts and provided with font distinguishing means embodying the present invention are distinguished and separated according to fonts. As shown in these figures, 1 represents the font distributor which is provided with channels 2 which respectively receive matrices of the same character but belonging to different fonts, the matrix channels being separated by vertically dividing walls or partitions 3, each dividing wall having a permuted rail 4 projecting therefrom into the matrix channel. In the present instance, each permuted rail is formed with permutations 5 which correspond with the permutations m^7 of matrices of the font represented by the matrix m^4 (Fig. 4); permutations 6 which correspond with the permutations m^8 of the matrices belonging to another font as represented by the matrix M^5 (Fig. 5), and permutations 7 corresponding with the permutations m^9 in all matrices belonging to another font and as represented by the matrix M^6 (Fig. 6). The matrix channels and the permuted rail 4 are preferably inclined longitudinally while the channels lie in vertical planes so that the matrices may descend within the channels by gravity while occupying vertical edgewise positions, the permuted rail being received in the recesses or grooves in the sides of the matrices and engaging the upper walls of these recesses, thereby supporting the matrices while travelling through the channels. In using such form of font distinguishing and separating means in conjunction with the improved matrices, all matrices of the font represented by the matrix M^3 (Fig. 3) will travel throughout the length of the permuted rail 4, the continuous or unpermuted upper edge or wall of its groove m^3 bridging the interruptions or permutations in the rail 4, and such matrices may pass directly through the font distributor and in a magazine at the lower end of the distributor. However, all matrices belonging to a font such as that represented by the matrix M^4 (Fig. 4) will travel downwardly on the permuted rail 4 until the permutations m^7 of such matrices register with the corresponding permutations 5 in the rail 4, at which point such matrices will be released from or unsupported by the rail 4, and hence free to drop directly edgewise and vertically by gravity through the

open bottom of the font distributor where they may be received and suitably directed into a second magazine. All matrices belonging to the font having distinguishing means as represented by the matrix M^5 (Fig. 5) will descend by gravity while supported on the permuted rail 4 until the permutations m^8 of such matrices reach or register with the permutations 6 in the rail, whereupon such matrices are free to drop directly edgewise and by gravity from the rail through the open bottom of the font distributor to be received by suitable means for directing them into a third magazine. In a similar way, all matrices belonging to a font having distinguishing means as represented by the matrix M^6 (Fig. 6) will descend by gravity along the permuted rail until the permutations m^9 of such matrices reach and hence register with the corresponding permutations 7 in the rail, whereupon these matrices will be free to drop directly edgewise and vertically from the rail through the open bottom of the font distinguisher where they may be received by suitable means such, for example, as that shown in my companion application, and directed into a fourth magazine.

Additional means is preferably provided for distinguishing the matrices by font, such additional distinguishing means being capable of use for the purpose of facilitating the separation and distribution of the matrices by font and preferably for the purpose of checking the movement of the matrices at the proper points in their travel along the permuted rail and to thus facilitate the release of the matrices at the proper points along this rail. To accomplish this result, it is preferable to form the recesses or grooves m^3 , m^4 , m^5 and m^6 of different relative widths, this being done in the present instance by so forming these recesses or grooves that their inner edges or walls will be in alinement with a line O—O, but their outer edges or walls will be located at relatively different distances from the adjacent longitudinal edge of the matrix. By forming the side recesses or grooves in this way, all matrices belonging to the same font will rest at the same elevation on the permuted rail 4, but the matrices belong to different fonts will occupy relatively different elevations on the permuted rail. This is represented clearly in Figures 2 and 7. By providing the upper wall of each matrix channel with graduated or stepped stops or shoulders 8, 9 and 10 in proper relation to the permutations 5, 6 and 7 respectively, of the permuted rail, the leading edges or feet of the matrices while descending through the font distributor will lodge against the stops or shoulders appropriate to these matrices, at which points the permutations in such matrices will register with the corresponding permutations in the rail 4 and the matrices

will thus be caused to release and drop promptly from the permuted rail. For example, in the particular construction herein shown, all matrices belonging to the font represented by the matrix M^3 will occupy a sufficiently low elevation on the permuted rail to clear all of the stops 8, 9 and 10, while such matrices are passing through the font distributor. However, all matrices belonging to the font represented by the matrix M^4 (Fig. 4) and which occupy a relatively higher elevation on the permuted rail while descending through the font distributor, will pass the stops 9 and 10, but will lodge against the stop 8, at which point the permutations m^7 in such matrices will register with the permutations 5 in the permuted rail, and hence such matrices will drop directly from the rail. Similarly, all matrices belonging to a font represented by the matrix M^5 (Fig. 5) will occupy a relatively higher elevation on the permuted rail while descending through the font distributor, and hence such matrices will pass the stop 10 but will lodge against the stop 9, the permutations m^8 in such matrices then registering with the corresponding permutations 6 in the permuted rail and hence such matrices will be released and they will drop directly from the rail. All matrices belonging to a font as represented by the matrix M^6 (Fig. 6) will occupy a higher elevation than those previously described, so that they will lodge against the stop 10, at which point the permutations m^9 of such matrices will register with the permutations 7 in the permuted rail, and hence such matrices will be caused to drop promptly from the rail. Obviously, by further extending the variations in the width of the side recess or groove in additional fonts of matrices, such font distinguishing means may be applied to a larger number of fonts, in which case additional suitably graduated or stepped stops may be used in the font distributor.

Matrices provided with means for distinguishing and separating them according to font or kind, substantially as herein described, are particularly suitable for use in cooperation with a font distributor of substantially the construction shown and described in my companion application hereinbefore referred to, but it is to be understood that the matrices may be provided with other distinguishing and separating means equivalent to these herein shown, and that such matrices may be used in cooperation with other forms of devices to secure separation or distribution of the matrices according to font.

The improved matrices possess the practical advantages that they may conform in outline with the ordinary matrices commonly used in machines of the linotype class so that they can be used for all purposes like the ordinary matrices, and, moreover, the

longitudinal recesses or grooves in the sides of the matrices may be increased in width, and also the number of notches leading out from these recesses or grooves and forming the permutations may be increased in the space between the lugs of the matrices to accommodate a larger number of fonts or sets without impairing the usefulness of the improved matrices as standard matrices.

10. I claim as my invention:—

1. Matrices each formed at a side thereof with a groove or recess extending longitudinally thereof, the grooves of dissimilar matrices being of different widths and distinguishing means formed in one edge of said groove and between the ears of the matrix.

2. A matrix having a groove formed in one of its sides and extending longitudinally thereof and distinguishing permutations in an edge of such groove and extending outwardly to the longitudinal edge thereof opposite to its character-bearing edge.

3. Matrices belonging to different fonts, each matrix having a recess extending longitudinally of the body and between the ears thereof, the recesses in matrices belonging to different fonts varying in width and constituting means to adjust the respective matrices to effect distribution thereof according to font.

4. A matrix having a groove extending longitudinally in one of its sides and openings at a right angle to such groove and extending outwardly to a longitudinal edge of the matrix for separating the matrix, according to font.

5. A matrix formed at one of its sides with a single groove extending longitudinally thereof between its ears and permuted notches extending from said groove to a longitudinal edge of the matrix between the ears thereof to distinguish and separate the matrix according to font.

45. 6. A font or set of matrices each having in its side a single groove or recess of pre-

determined width extending longitudinally thereof and permuted notches of predetermined location between the ears of the matrix and extending at a right angle to such groove to distinguish and separate such matrices according to font.

7. A plurality of fonts or sets of matrices, each matrix of each font having a groove and permutations in one edge of the groove, the grooves of all matrices belonging to the same font being alike and the grooves of matrices belonging to the different fonts being located at different distances from one of the longitudinal edges of such matrices.

8. A plurality of fonts or sets of matrices each matrix of each font having a groove, the groove in all matrices belonging to the same font being of the same width and distance from a longitudinal edge thereof and the grooves in the matrices belonging to the different fonts being respectively of different widths and respectively at different distances from a longitudinal edge thereof.

9. A plurality of fonts or sets of matrices, each matrix of each font having a groove extending longitudinally in a side thereof, and font distinguishing notches leading from such groove to an adjacent edge of the matrices, the notched edge of said grooves being at an equal distance from the adjacent longitudinal edge of all matrices belonging to the same font but located at different distances from such longitudinal edge of matrices belonging to different fonts.

10. A plurality of fonts or sets of matrices, each matrix of each font having a groove in one of its sides and permuted notches extending from such groove to an adjacent edge of the matrix, the grooves being positioned alike in all matrices belonging to the same font but differing in matrices belonging to different fonts.

In testimony whereof I have hereunto set my hand.

HERMAN R. FREUND.
